Primary Examiner—Cynthia M Chin*(74) Attorney, Agent, or Firm*—Steven L. Nichols; Van Cott, Bagley, Cornwall & McCarthy PC(57) **CLAIM**

The ornamental design for a bottle handle, as shown and described.

DESCRIPTION

FIG. 1 is a front perspective view of a bottle handle showing the new design.

FIG. 2 is a back elevation view of the bottle handle.

FIG. 3 is a right side elevation view of the bottle handle.

FIG. 4 is a top plan view of the bottle handle.

FIG. 5 is a left side elevation view of the bottle handle; and, FIG. 6 is a front elevation view of the bottle handle.

The broken lines represent the environment in which the design resides and forms no part of the claim.
